[57] CLAIM

The ornamental design for a tailgate latch, as shown and
described.

DESCRIPTION

FIG. 1 is a perspective view of a tailgate latch showing
my new design, the broken-line depiction of a second
latch and tailgate assembly being for illustrative pur-
poses only and forming no part of the claimed design;
FIG. 2 is an enlarged perspective view thereof;
FIG. 3 is an enlarged side elevational view thereof, the
opposite side being a mirror image of that shown;
FIG. 4 is an enlarged end elevational view thereof;
FIG. 5 is an enlarged opposite end elevational view
thereof;
FIG. 6 is an enlarged top plan view thereof; and
FIG. 7 is an enlarged bottom plan view thereof.
